[57] CLAIM

The ornamental design for a wide mouth vacuum container with flexible strap, as shown and described.

DESCRIPTION

FIG. 1 is a front elevation view of the wide mouth vacuum container with flexible strap showing my new design; FIG. 2 is a side elevation view thereof, the opposite side being identical except for not having the elliptical shape in the middle portion;

FIG. 3 is a rear elevation view thereof;

FIG. 4 is a top plan view thereof with the cover removed for clarity of illustration;

FIG. 5 is an exploded side elevation view thereof; and, FIG. 6 is a bottom plan view thereof.
